UNITED STATES PATENT OFFICE.

DAVID ZINN, OF NEW HAMBURG, ONTARIO, CANADA.

SNOWPLOW.

Application filed May 17, 1926. Serial No. 109,618.

This invention relates to improvements in snow-plows and has for its primary object to provide a device of this character that may be installed upon the forward end of a conventional tractor in order that the same may be pushed along a road or public highway to clear the snow therefrom, the device being operatively connected to the power take off shaft of the tractor.

An additional object of the invention is to provide a device of this character that may be readily associated with a conventional form of tractor without altering the construction of the tractor and without requiring any unusual skill in the application of the plow to the tractor.

Other objects will become apparent as the nature of the invention will be better understood, the same comprising the novel form, combination, and arrangement of parts hereinafter more fully described, shown in the accompanying drawings and claimed.

In the drawings wherein like numerals designate like parts throughout the several views:

Figure 1 is a side elevation of my improved snow plow as actually associated with a conventional form of tractor.

Figure 2 is a bottom plan view of the tractor and plow.

Figure 3 is an enlarged top plan view of the snow plow per se.

Figure 4 is a front end elevation thereof.

Figure 5 is a detail longitudinal section, and

Figure 6 is an enlarged top plan view of a supporting and steering skid for the plow that is operatively connected with the steering wheels of the tractor in order that the plow will be guided in the same direction with the tractor.

Now having particular reference to the drawings, 5 designates generally a conventional tractor which is disclosed as being one of the Fordson type, the construction of which is well known and even a general description is therefore not necessary. My device constitutes the provision of a pair of spaced parallel and horizontal frame bars

6-6 that are so constructed as to permit the inner ends of the same to be bolted or otherwise rigidly secured to the forward end of the chassis bars of the tractor as clearly dis-

closed in both Figures 1 and 2. The forward ends of these bars 6-6 are formed with depending arms 7 from the lower ends of which extend forwardly projecting and downwardly inclined bars 8 upon which is supported a relatively large frusto conical fan housing 9, the bottom wall of which is so formed as to present a horizontal front edge as clearly disclosed in Figure 4, and to which horizontal edge is pivotally connected a horizontal plow blade 10 that is equipped at its forward edge with spaced teeth 11 that will bite into the snow and cause the same to be fed upwardly upon the plow blade into the housing in an obvious manner.

Arranged transversely upon the bars 6-6 are a pair of spaced parallel beams 12-12 that are interconnected at their opposite ends by cross bars 13-13. Journaled within bearings 14 intermediate the ends of the beams 12-12 is a longitudinal shaft 15 that extends forwardly through an opening 16 in the rear wall of the housing 9 and projects outwardly thereof as more clearly disclosed in Figure 5 at which outer end the same is provided with a snow cutting auger 17. At the projecting end of the shaft 15 directly rearwardly of this auger said shaft is supported by depending shaft hanger 18 anchored at its upper end to the top side of the housing 9, as shown more clearly in Figures 1 and 3.

Suitably journaled between the beams 12-12 supported upon the frame bars 6-6 at the right hand side of the shaft 15 is a transverse shaft 19 that is equipped at its inner end with a beveled gear 20 in mesh with a bevel gear 21 upon said shaft 15. This shaft 19 is equipped intermediate its ends with a belt pulley 22 over which is trained an endless belt 23 that extends rearwardly and is in turn trained over the pulley mounted upon the power take off shaft of the tractor as clearly disclosed in Figure 2 in order that when the said power take off shaft is operated, rotation will be imparted to the shafts 19 and 15 of the snow plow construction.

Mounted upon the shaft 15 within the housing 9 is an auger fan unit 24 that will force the snow fed into the housing in a rearward direction and cause the centrifugal

action of the same in order to discharge the snow through an exhaust opening 25 in the top of the housing and at the rear side thereof, and from which said exhaust opening leads a laterally extending pipe 26 to convey the snow to the side of the roadway.

Mounted at the opposite sides of the housing 9 are snow cutting reels 27-27 that serve to permit the plow and tractor to pass between the snow banks without interference, said reels consisting each of a vertically inclined shaft 28 suitably journaled at its opposite ends and being equipped at its upper end with a beveled gear 29 that is in mesh with a beveled gear 30 upon the forward end of a shaft 31 extending along the adjacent sides of the housing and being equipped at its rear end with a beveled gear 32. The gears 32 of the shafts 31 are in mesh with beveled gears 33-33 upon the ends of a shaft 34 which is arranged in parallel relation with the heretofore described beams 12-12 and is journaled at its opposite ends within suitable bearings arranged upon the beam connecting bars 13-13. Said shaft 34 is equipped with a spur gear 35 adjacent its right hand end, the teeth of which are in mesh with the teeth of a similar gear 36 upon the heretofore mentioned shaft 19 in order that when said shaft 19 is rotated by reason of the power take off shaft of the tractor such rotation will be imparted to the shafts 31 and consequently the cutting reels 27-27 will be operated for a purpose heretofore described.

Mounted beneath the fan housing supporting bars 8 is a horizontal board 37 to the center of which is pivoted as at 38 a horizontal skid board 39 equipped at its outer ends with sleigh runners 40-40. The pivotal connection 38 between said boards 37 and 38 extends loosely between cross slots in the respective boards as clearly disclosed in Figures 2, 5 and 6, said slots permitting the skid to have a limited transverse and longitudinal sliding movement to facilitate the proper steering of the plow when the front steering wheels of the tractor are turned in a manner hereinafter more fully described.

Secured to the rear ends of the runners of the skid are the forward ends of chain lengths 41-41 which chain lengths are extended diagonally across the under side of the plow in opposite directions and are then trained over pulleys 42-42 supported from the depending arms 7, as shown in Figures 2 and 5. The chain lengths are then extended diagonally beneath the plow in opposite directions and are secured at their inner ends to arms 43-43 that are attached to the wheels supporting spindles of the tractor front steering wheel in order that when said wheels are turned for steering the tractor, a corresponding movement of the

skid will be occasioned for guiding the plow in similar directions with that of the tractor.

The forward ends of the runners 40-40 of the skid have connection with chain lengths 44-44 that are extended inwardly and toward the front end of the housing 9 at which point they are anchored as at 45, said chain lengths 44-44 obviously tending to hold the skid from pivoting which tendency will necessitate the skid moving in a longitudinal and transverse direction prior to the actual turning of the same upon its pivot to facilitate the proper steering of the plow with respect to the steering of the tractor.

It will thus be seen that I have provided a highly novel, simple, and efficient form of snow plow that is well adapted for all the purposes heretofore designated and even though I have herein shown and described the invention consisting of certain detail structural elements it is nevertheless to be understood that departures may be had therefrom without effecting the spirit and scope of the appended claims.

Having thus described the invention, what I claim as new and desire to secure by Letters Patent is:—

1. In a snow plow for tractors, a pair of horizontal frame bars secured at their inner ends to the forward ends of the tractor chassis bars, the outer ends of said frame bars being disposed downwardly and thence forwardly, the forwardly projecting ends of the frame bars being inclined downwardly, snow gathering means mounted on the inclined forwardly projecting ends of said frame bars, means whereby said snow gathering means may be operated by the tractor power plant, a board mounted transversely beneath the inclined forwardly projecting ends of the frame bars, an underlying board, runners at the outer ends of said underlying board, a pivotal connection between said boards, and means for connecting the runners to the tractor steering wheels for facilitating the steering of the runners.

2. In a snow plow for tractors, a pair of horizontal frame bars secured at their inner ends to the forward ends of the tractor chassis bars, the outer ends of said frame bars being disposed downwardly and thence forwardly, the forwardly projecting ends of the frame bars being inclined downwardly, snow gathering means mounted on the inclined forwardly projecting ends of said frame bars, means whereby said snow gathering means may be operated by the tractor power plant, a board mounted transversely beneath the inclined forwardly projecting ends of the frame bars, an underlying board, runners at the outer ends of said underlying board, a pivotal connection between said boards, means for connecting the runners to the tractor steering wheels for facilitating

the steering of the runners, said last mentioned means including a pair of diagonally disposed chains secured at their forward ends to the rear ends of the runners, the 5 other ends of the chains being secured to the respective steering wheel spindles, and a pair of anchoring chains anchored at their for-

ward ends, the rear ends of the last mentioned pair of chains being secured to the forward ends of said runners for limiting the movement thereof.

In testimony whereof I affix my signature.

DAVID ZINN.
